EXTRACTOR

William H. Woodward, Detroit, Mich.

Application July 9, 1932, Serial No. 621,592

8 Claims. (Cl. 100—50)

This invention relates to extractors, and particularly to devices for extracting moisture from articles or material by placing the same in a collapsible receiver and subjecting the latter to exterior pressure to effect its collapse.

In extracting liquid from articles or material by applying exterior fluid pressure to a collapsible bag or the like having an opening at its top for inserting the articles or material, it commonly happens that the bag is not completely filled. Also, whether or not the bag is filled, the articles or material in the lower portion of the bag, because of the superposed weight, offer a greater resistance to compression than the upper portion 15 of the bag contents. Hence collapse of the upper portion of the bag under external pressure tends to exceed that of its lower portion, compelling the liquid extracted from the main body of material under compression to pass through a 20 region of still greater compression to reach the receptacle outlet and thus sacrificing efficiency.

An object of the invention is to provide an extractor of the above mentioned general character in which the collapsible receiver has the nature 25 of an open-topped receptacle formed of rubber or the like, and in which a simple and inexpensive provision is made for applying fluid pressure exteriorly to said receptacle to extract liquid from its contents.

Another object is to equip such an extractor 30 with a cover having an outlet or outlets for the extracted liquid, and to fasten said cover in place by a means adequate to resist the pressure under which extraction is effected, while affording ready removal of said cover to permit filling and emptying the receptacle.

Still another object is to provide a receptacle 35 collapsible to extract liquid from its contents and having an outlet for such liquid, the flexibility of the receptacle wall being increased as said wall recedes from said outlet, whereby the contents of said receptacle are safeguarded against a greater compression between the outlet and opposed wall of the receptacle than prevails adjacent to said wall.

A further object is to provide a collapsible receptacle for extractor purposes having its wall 40 gradually reduced in thickness from its mouth to its bottom, adapting said receptacle to yield, progressively from its bottom to its mouth, to an exteriorly applied fluid pressure, and effecting a uniform compression of its contents.

A still further object is to progressively decrease 45 the diameter of such a receptacle from its mouth to its bottom, to facilitate a telescoping of the

lower portion of said receptacle within its upper portion, responsive to an exteriorly applied fluid pressure.

These and various other objects the invention attains by the construction hereinafter described, and illustrated in the accompanying drawing, 5 wherein:

Fig. 1 is a top plan view of the improved extractor, with a portion of its cover broken away.

Fig. 2 is an axial, sectional view of the same, 10 taken upon the line 2—2 of Fig. 1.

Fig. 3 is a vertical sectional detail upon the line 3—3 of Fig. 1, showing one of the fasteners holding the cover in place.

In these views, the reference character 1 designates an open-topped cylindrical casing formed preferably of sheet metal having a portion 2 adjacent its mouth of an enlarged diameter, and connected by an annular shoulder 3 to the main body of said casing.

Positioned within said casing and spaced from its side walls and bottom, is a collapsible open-topped receptacle 4, having its wall flaring gradually toward its top, and having the thickness of said wall progressively reduced from top to bottom, the bottom thickness being preferably uniform.

Said receptacle is formed preferably of rubber, and is characterized by a ready flexibility of its wall, and also preferably of its bottom, and by nonpermeability of its wall and bottom to fluids. Marginally of its mouth, the receptacle 4 is formed with an annular outstanding flange 5, seating upon the shoulder 3 and suitably held in fluid-sealing engagement with said shoulder. As illustrated, this is accomplished by a metal ring 30

superposed on the flange 5 and connected through said flange to the shoulder 3 by rivets 35

7. A circular sheet metal cover 8 is adapted to marginally seat upon the ring 6, and is formed in its outer portion with a number of circumferentially spaced key-hole slots 9, through which may project headed studs 10 rigidly upstanding from the ring 6, whereby a slight rotative actuation of the cover serves to latch it in place. Said cover is further formed with a plurality of per-

forations 11, through which liquid may rise in use of the extractor.

The portion 2 of the casing is formed at a suitable point in its peripheral wall with a spout 12 adapted to discharge such liquid as rises through 40 the perforations 11. In its lower portion, the casing is provided with suitable valved inlet and outlet pipes 13 and 14.

In the use of the described extractor, the receptacle 4 is initially filled to any desired level 45

with washed garments or other articles or material requiring an extraction of liquid. The cover 8 is now applied and latched in place. The casing outlet 14 being closed, a fluid under suitable pressure is admitted at 13 to the casing.

Yielding to said fluid, the receptacle 4 progressively collapses from its bottom upward, the bottom rising within the receptacle wall and the lower portion of the receptacle telescoping in its upper portion. Such collapse follows from the described variation in thickness of the receptacle wall and inverse variation of its resistance to collapse. The contents of the receptacle are thus forced upwardly against the cover plate, and are, in part, at the same time compressed between the telescoping inner and outer portions of the receptacle wall. This has the effect of preventing any compression of the upper or an intermediate portion of the receptacle contents in excess of the compression at the same time applied to the bottom portion of the contents, and hence avoids undue resistance to the flow of liquid extracted from the lower portion of the material in the receptacle. When the material has been brought into firm engagement with the cover member, as has been described, the fluid pressure may be continued, and if desired, increased until extraction has been carried to the desired point, the thicker portion of the receptacle wall now yielding inwardly in addition and adding to the compression applied upwardly to the receptacle. The extracted liquid arises through the perforations of the cover 8 and discharges from the cover through the spout 12.

The described construction is simple and inexpensive, and its operating cost is a minimum, since the energizing pressure may be that of water derived from city mains.

Said device is widely applicable in effecting an extraction of liquid from washed clothes, and is particularly suitable for household use. It may be designed for numerous other applications, as for example, extraction of juices from fruits.

While it is apparent that the illustrated embodiment of my invention is well calculated to adequately fulfill the objects and advantages primarily stated, it is to be understood that the invention is susceptible to variation, modification and change within the spirit and scope of the subjoined claims.

What I claim is:

1. In an extractor, a collapsible, open-topped, flexible walled receptacle having a closed bottom having its lower portion of a lesser diameter and of a greater flexibility than its upper portion, whereby the lower portion tends to collapse within the upper portion under externally applied fluid pressure.

2. An extractor comprising an open-topped casing forming a fluid pressure chamber, and having a fluid inlet and outlet, a collapsible open-topped receptacle suspended within said casing, a cover member perforated throughout substantially its entire area, detachably secured to said casing and clamping said receptacle, marginally of its opening upon the casing, marginally to the casing opening, the receptacle being relatively stiff in its upper portion, whereby said portion resists displacement against said cover member and consequent obstruction of perforations of said cover member, under pressure of fluid in said chamber.

3. An extractor comprising an open-topped casing forming a fluid pressure chamber, a flexible-walled collapsible, open-topped receptacle se-

cured marginally of its top opening to the margin of the top opening of the casing and thereby suspended within the casing, a cover member for said receptacle having a plurality of openings forming liquid outlets from the receptacle, and means detachably securing said cover member to the casing, the receptacle having a relatively stiff upper portion resisting flexure of said portion against the cover member and resultant closing of one or more of said cover member openings.

4. An extractor, comprising an open-topped casing, a flexible-walled, collapsible, open-topped receptacle for material requiring an extracting operation, secured marginally of its top opening to and suspended within the casing, and forming with the casing a fluid pressure chamber, means for delivering a fluid under pressure to such chamber, a cover member for said receptacle affording a discharge of extracted liquid, and means detachably securing the cover member to the casing, the receptacle wall being of greater flexibility in its lower portion than in its upper portion, whereby there is precluded excessive yielding of the upper portion to applied fluid pressure and consequent undue resistance to discharge of liquid from the lower portion.

5. An extractor as set forth in claim 4, said receptacle having the flexibility of its wall gradually increased from top to bottom of said wall.

6. An extractor as set forth in claim 4, said receptacle having the thickness of its wall gradually reduced from top to bottom of said wall.

7. An extractor comprising a flexible-walled, collapsible receptacle for material requiring an extracting operation, said receptacle having at one end an opening for inserting and removing such material and for the discharge of an extracted liquid, the other end of the receptacle being closed, a casing receiving said receptacle and forming therewith a fluid pressure chamber, the casing having an opening and the receptacle being secured marginally of its end opening to the margin of the casing opening, means for delivering a fluid under pressure to said chamber, and means for retaining the material being treated within the receptacle during extraction, the wall of the receptacle being progressively increased in flexibility as it recedes from the receptacle opening, and having a stiffness adjacent to the opening, precluding undue restriction of the receptacle in advance of the liquid undergoing extraction.

8. In an extractor, a flexible-walled, collapsible receptacle for material requiring an extracting operation, said receptacle having an opening at one end for inserting and removing material requiring an extracting operation, and for the discharge of an extracted liquid, and being closed at its opposite end, means for supporting the receptacle marginally of such opening, means for applying fluid pressure externally to the receptacle, and means for retaining the material being treated within the receptacle during extraction, the closed end of the receptacle having a greater flexibility than the receptacle wall, and the cross-sectional area of the receptacle being progressively decreased from its opening to its closed end, said end being thereby yieldable toward said opening under externally applied fluid pressures.

WILLIAM H. WOODWARD.
